UNITED STATES PATENT OFFICE

2,371,903

FLOODLIGHT BRACKET

John W. Maier, Bellingham, Wash.

Application August 26, 1943, Serial No. 500,121

1 Claim. (Cl. 248—226)

The present invention relates to a floodlight bracket and more particularly to an adjustable floodlight bracket and floodlight combination adapted to be rapidly mounted and adjusted in position to direct light upon the work in a manner to conform readily to dim-out regulations in shipyards, airplane manufacturing plants, and other manufacturing plants, particularly those engaged in the production of war materials requiring substantially continuous production.

In large-scale manufacturing operations, as in the building of ships, in which continuous operation is required, it is impractical to maintain the required illumination throughout a plant together with provision for black-outs or to conform to dim-out regulations, and the provision of sufficient illumination with the necessity of shifting the location of the work to provide for the carrying out of subsequent operations, after each operation has been completed, has been not only difficult, but time consuming, resulting in a slow down of operations.

One of the objects of the present invention is to provide a form of floodlight support and floodlight combination which may be readily mounted upon fixed objects which are generally available in manufacturing plants, such as supporting columns, beams, and the like, and which may be readily carried or transported from one location to another in a plant, factory or other building in which it is to be used.

Another object of the invention is to provide a form of floodlight support and floodlight combination which may be rigidly fixed in a desired position upon a column, beam or other support and which is provided with means for adjusting the direction of illumination in both a vertical and horizontal plane, so that as the work is shifted in position or turned, the direction of the light may be accordingly changed to provide the desired path of illumination.

Another object of the invention is to provide a form of floodlight bracket which is simple in operation and rugged in construction so that it may be operated and used by substantially any class of help, whether skilled or unskilled, and which may be manufactured at a relatively low cost of production.

Another object of the invention is to provide a form of floodlight bracket upon which a floodlight may be readily mounted in adjustable position and which is provided with mounting means adapted to be readily moved into the desired approximate position for fitting approximately a column or beam of any ordinary size and with

final clamping or adjusting means having lever means for applying a high tightening force in the final secured position, so as to prevent any accidental displacement of the bracket.

With these and other objects in view, the invention comprises the various features herein-after more fully explained and defined in the annexed claims.

The invention is illustrated in its preferred form in the accompanying drawing, in which:

Fig. 1 is a view in elevation showing the floodlight bracket and floodlight combination, illustrating the manner in which the device of this invention is to be mounted upon an upright column or beam; and

Fig. 2 is a detailed view in perspective of the adjustable floodlight bracket of the invention, showing the detailed construction thereof.

Referring more in detail to the drawing, the numeral 2 designates the adjustable floodlight bracket of the invention as a whole and the numeral 4 designates the adjustable floodlight or lighting fixture.

The floodlight bracket in its preferred form 25 comprises a main frame member or portion 6, in the form of an angle iron having the main frame extension 8 and a short arm member 10 transverse thereto, or in other words, bent at right angles to the main frame portion. Connected to the outer side of the main frame portion 8, and preferably welded thereto, is a projection or boss member 12 having an opening 14 therein in which the floodlight or lighting fixture may be mounted and fixed in adjustable position.

In order to provide means for obtaining an approximate fit on the column or beam on which the floodlight bracket is to be mounted, so that a relatively slight movement of parts will suffice to bring the supporting members into holding engagement with the column or beam, a movable or sliding arm member 28 bent in the form of an angle iron, and having a part 30 adapted for sliding engagement with the under side of 30 the main frame portion 8, and a transverse part 32 at right angles thereto are employed, which are adapted to cooperate with the arm member 10 and the support 48 in the manner hereinafter described. In order to obtain the approximate fit, a series of notches 16, 18, 20, 22 and 24 are provided along one edge 9 of the main portion 8, preferably the upper edge when the bracket is mounted with the lever member 46 to the right as shown in Fig. 1. Pivotedly mounted on 35 the transverse part 32 is a bar member or pawl

26, which is preferably attached to the inner or left side of the part 32, with reference to Fig. 2 of the drawing, by means of the set screw or stud 40, as indicated in the drawing. In order to maintain the slidable member 28 in engagement with the main body portion 8 of the main frame, lateral extensions 38 and 44 may be bent around the main frame member 8, so that the part 32 may be moved backward and forward over the under surface of the said member. It will be understood that a separate ring member might be used for this purpose, although the construction illustrated is simpler in operation and constructional features. In order to hold the slidable member 32 in the approximate adjusted position, the end 27 of the pawl or pin member 26 is inserted into the nearest notch, as 22, which permits the transverse arm members 10 and 32 to extend beyond the adjacent sides of the column or beam on which the bracket is to be mounted. It will be apparent that when the bracket is held in the position indicated in Fig. 1 of the drawing, the bar member or pawl will be held by gravity in engaged position in a notch until it is lifted out of engagement therewith.

In order to obtain the desired lever action in securing the bracket member in its final adjusted position, a lever member 46 is provided, which is screwthreaded along one arm thereof at 31, and passes through an internally screwthreaded boss 11 mounted on the arm member 10 so as to extend at right angles to the inner surface of the transverse arm member 32. The screwthreaded portion of the lever member 46 is provided at its extreme end with a knob member 48, having a curved outer surface for engagement with the flat surface of a column or beam on which the bracket is mounted. If a wooden beam or post is used for mounting the bracket member thereon, the knob member will be forced inwardly by means of the lever action of the lever 46 and the screw 31, so that the bracket member will be held in place by a relatively high leverage force. It will be understood that the knob member 48 may be mounted on the end of the lever member 46 in any desired manner, but it is preferably so mounted that the end of the lever arm turns on the adjacent side of the knob so that the outer contacting face of the knob does not turn on the face of the beam or column with which it is in contact.

In order to provide an adjustable mounting for the floodlight or light on the bracket, I preferably employ adjustable holding means which may be readily fixed in position on the bracket and which is adapted to be moved in a plane substantially at right angles to the plane of movement of the bracket member, so as to provide in effect a universal joint support for the floodlight or lighting element. For this purpose, the lighting fixture including the reflector 52 and fittings may be fixed or attached to the boss or extension 12 by means of a 45 degree elbow 60 in such a manner as to permit relative movement or swinging movement in the 45 degree plane or cone about a vertical axis passing through the opening 14. The detailed construction which is preferably employed may be described with reference to Fig. 1 of the drawing. A one-half inch nipple 54 may be used for mounting in the opening 14 by means of locknuts on each side of the extension 12. A locknut 56 is preferably welded to the lower side of the nipple 54 and the nipple is then inserted from the underside through the opening 14. Another locknut 58 is then screwed

onto the upper side of the nipple so as to hold the nipple in place in the said opening. The 45 degree elbow 60 is then screwed into place on the upper or exposed end of the nipple 54, so that the elbow is turned outwardly from the bracket as shown in Fig. 1 of the drawing. Another nipple 62 is then screwed into the upper end of the elbow or 45 degree pipe fitting 60, and locknuts 64 and 66 are provided over the nipple 62 to hold the parts in fixed adjusted position. In order to attach the floodlight or lighting fixture, the electric socket 68 is then screwed in place on the nipple 62 so that the reflector 52 extends outwardly from the plane of the bracket and the locknuts are screwed into place so that the floodlight or lighting fixture is rigidly secured in position.

Assuming that the floodlight is to be moved from one position to another in a plant so as to obtain light directly on the work which is to be operated upon. The handle of the lever 46 is unscrewed so that the bracket 2 may be removed from the beam or post 50. The plug connected to the cord 70 is then pulled out of the electric light receptacle and is then plugged in in an outlet box near the work which is to be lighted. The floodlight bracket may then be mounted on the nearest column, beam or post whether it extends vertically or horizontally, although a rigid vertical timber is preferred. Assuming that a vertical column is located near the work, the handle 46 is first unscrewed so as to bring the knob 48 near the inner surface of the arm 10. If the column is three inches thick, for example, the slidable member 32 is moved so that the distance between the arm 32 and the knob 48 is a little more than three inches and the bracket is then placed around the beam or column and the locking bar or pawl 26 is then dropped into the proper slot, the main frame member of the bracket having been placed so that the edge 9 containing the slots is uppermost. The handle of the lever 46 is then turned so that the knob 48 is pressed onto the face of the column and the points or projections 34 and 36 at the ends of the arm 32 penetrate or firmly grip the surface of the column with which they are in contact, and the floodlight is then held firmly in position so as not to be accidentally displaced without the application of considerable force or caused to swing or be moved by wind or drafts.

If it is desired to change the direction of the floodlight in a vertical position, as up or down, it is necessary only to loosen the bracket tension handle 46 and then tilt the light up or down in the desired direction and again tighten the handle by turning it into secured position. If it is desired to swing the floodlight to the right or left in the plane of the 45 degree conical surface or other plane, depending on the extent of the bend of the elbow member 60, all that is required is to loosen the upper locknut 58 and swing the light through the proper angle so that the light falls on the work and then tighten the said upper locknut 58 in place.

It is to be understood that various changes or modifications may be made in the device as above described and as illustrated in the drawing without departing from the spirit or scope of the invention as defined in the annexed claim. For example, in place of the 45 degree pipe fitting or elbow 60, I might employ a right angled fitting or a 30 degree elbow or other fitting as might be required in connection with some specialized work requiring lighting from a definite angle,

depending on the nature of the operation required on the work. It is to be understood, also, that in place of the handle 46 as shown, a crank having a handle extension at right angles to the extension 46 might be used, and other similar modifications may obviously be made by those skilled in the art in other parts of the structure of my invention without departing from the scope of the invention as defined. As illustrated in the drawing, and as above described, the locking bar 26 is preferably pivotally mounted on the inside of the transverse member 32, so as to be adjacent the beam or timber to which the flood-light bracket is to be attached. It has been found by experiment that there is more danger of the locking bar 26 being dislodged or broken off if it is mounted on the outside of the transverse member 32, or away from the beam or timber on which the bracket is mounted. It is to be understood that the locking bar is only a safety feature, as the flood-light bracket locks itself on any beam which is four inches or more in thickness. In the ordinary dimensions of the flood-light bracket, the locking bar may be only an inch and a half long, and in its hinged position on the transverse jaw member 32, it gives an inch and three quarters clearance to the points 34 and 36 of the jaw. In the same size bracket, the locking bar may be made an inch long so as to give an additional half inch clearance from the points 34 and 36, or other suitable dimensions may be used as will be obvious to those skilled in the art. It is to be understood that I do not desire to be limited to definite dimensions or pro-

portions except as defined by the claim annexed hereto.

Having thus described the invention, what is claimed as new is:

- 5 A floodlight and floodlight bracket combination adapted for use in structures subject to dim-out regulations which comprises an angle-bracket frame member having a longitudinally extending body portion and a fixed transverse jaw portion,
10 15 20 25 30 a series of spaced indentations along one lateral edge of the main body portion, a movable transverse jaw member slidably mounted on said body portion, a locking member adapted to cooperate with said indentations for locking the said transverse jaw member in a fixed position relative to the body member, said locking member being pivotally mounted at one end thereof on one face of said slidably transverse jaw member for movement into and out of engaging relation with said indentations, a screw member mounted on said fixed jaw portion for movement at right angles thereto for locking the bracket in position, a lever connected to said screw member for screwing and unscrewing the same, swivel mounting means connected to said angle bracket frame member, and a floodlight connected to said swivel mounting means, said swivel mounting means including an elbow mounting member having threaded portions thereon and locknuts fitting the said threaded portions for locking the floodlight in a fixed angular position with respect to the body portion of the bracket.

JOHN W. MAIER.
